UNITED STATES PATENT OFFICE

DANIEL J. HAFFORD, OF CLEVELAND, OHIO, ASSIGNOR TO THE CLEVELAND ROCK DRILL COMPANY, OF CLEVELAND, OHIO

DRILL STEEL RETAINER

Application filed February 25, 1928. Serial No. 256,923.

The present invention is directed to improvements in drill steel retainers.

The primary object of the invention is to provide a device of this character so constructed that the drill steel will be effectively held in its operative position when the drill is operating, the construction being such that the steel can be easily and quickly removed and replaced.

Another object of the invention is to provide a device of this kind wherein the retainer will be prevented from swinging open when the drill steel collar encounters the same, thus holding the drill steel against accidental disengagement from the front head.

Another object of the invention is to provide a device of this character which is extremely simple in construction, and one wherein when the drill steel collar strikes the retainer the shock incident thereto will be absorbed, thus prolonging the life of the retainer.

In the accompanying drawings:

Fig. 1 is an elevational view of the front head of a drill having the improved retainer attached thereto, part being broken away to more clearly show the construction;

Fig. 2 is a sectional view taken on a plane indicated by the line 2—2 in Fig. 1;

Fig. 3 is a detail elevational view; and

Fig. 4 is a sectional view taken on a plane indicated by the line 4—4 in Fig. 1.

Referring to the drawings, 1 designates the front head of a percussive drill and from one side thereof projects a lug 2, said lug having an opening 3 formed therein. The front head as usual is constructed to receive the drill steel 4, which in this instance is provided with a collar 5.

The under surface of the lug is provided with a short rib 6, the purpose of which will be later explained. Slidable in the opening 3 is a shank 7, which is threaded for the application of the clamping nut 8, and encircling said shank is a coil spring 9, one end of which bears against the nut while the other end engages the adjacent face of the lug 2.

The shank has its lower end terminating in a head 10, said head having a vertically disposed slot 11 formed therein and communi-

cating with an angularly disposed entrance opening 12. In this manner a hook 13 is provided which serves to pivotally connect the steel retainer per se to the front head for operation.

The retainer 14 consists of angularly disposed sections 15 and 16, the latter having a slot 17 formed therein which communicates with an opening 18 formed in the section 15, said opening being of such diameter that the collar 5 of the drill steel may pass therethrough, whereas the slot is of such size as to arrest the movement of said collar.

The section 15 is provided with an extension 19, which is arranged to non-rotatably engage in the lower end of the slot 11 below the entrance opening 12, as shown in full lines in Fig. 1. The extension 19 is disposed at such an angle to the section 15 as to hold the retainer against swinging movement with the slot 17 engaging about the drill steel shank. The retainer may be pivoted to the position shown in dotted lines in Fig. 1 by raising the same vertically until the extension 19 clears the hook 13.

In order to prevent the head 10 from turning the upper surface thereof has a recess 21 formed therein and in which the rib 6 engages. It will be of course obvious that the spring 9 will yieldably hold the head engaged with the lug 2.

As shown in full lines in Figure 1, the extension 19 is engaged with the hook or in the lower end of the slot 11, thus holding the retainer in a position to maintain its slot 17 engaged with the drill steel 4, and owing to the fact that this slot is of less diameter than the collar 5 passage thereof through said slot is prevented. Since the extension 19 fits snugly in the lower end of the slot 11 the drill steel can be pulled from a hole when stuck, owing to the fact that when the retainer is in this position it will be held against swinging movement. When it is desired to remove the steel from the front head the retainer is moved upwardly until the extension 19 can be tilted, whereupon the opening 18 will be aligned with the collar 4 to permit the same to pass therethrough.

It will be of course understood that any

shock imparted to the retainer will be absorbed by the spring 9, which also serves to maintain the rib 6 engaged in the recess 21, thereby preventing the head from rotating. In this manner the head will be at all times held in proper relationship with respect to the drill steel.

5 What is claimed is:—

10 1. The combination with the fronthead of a drill, of a lug carried thereby, a shank engaged in the lug and having a head, said head having a longitudinal slot formed therein forming a hook, a drill steel retainer comprising angularly disposed sections provided 15 with a communicating opening and slot, a collared drill steel operatively connected with the fronthead, one of the sections having an extension for non-rotatable engagement with the bill of the hook to maintain the said slot in the path of movement of the drill steel collar, and releasable therefrom to permit the opening to be positioned to permit the passage of the collar therethrough.

20 2. The combination with the fronthead of a drill, a lug carried thereby, a shank yieldably maintained in the lug, said shank having a head provided with a longitudinal slot and entrance opening communicating with the slot, a drill steel having a collar operatively connected with the fronthead, a drill steel retainer including angularly disposed sections provided, respectively, with a slot and an opening, one of the sections having an angularly disposed extension carried thereby for passage through the entrance opening for non-rotatably engaging in the lower end of the first named slot to hold the retainer in a position to prevent passage of the collar through the slot of the retainer.

25 3. In testimony whereof I affix my signature.

DANIEL J. HAFFORD.
